DESIGN.

H. SMITH & F. A. SEIFERT.
HEATING STOVE.

No. 18,768.

Patented Nov. 27, 1888

UNITED STATES PATENT OFFICE.

HOLMES SMITH AND FRANK A. SEIFERT, OF ST. LOUIS, MISSOURI, ASSIGNEES TO THE BRIDGE AND BEACH MANUFACTURING COMPANY, OF SAME PLACE.

DESIGN FOR A HEATING-STOVE.

SPECIFICATION forming part of Design No. 18,768, dated November 27, 1888.

Application filed September 13, 1888. Serial No. 285,343. Term of patent 14 years.

To all whom it may concern:

Be it known that we, HOLMES SMITH and FRANK A. SEIFERT, of St. Louis, Missouri, have jointly invented and produced a new and original Design for Heating-Stoves, of which the following is a full, clear, and exact description, reference being had to the accompanying engraving, forming part thereof, in which the newly-designed stove is shown in perspective.

The design in question relates partly to the configuration of the stove, especially the stove-body, and partly to the ornamentation appearing upon the stove.

15 The stove body A, so far as its general outline is concerned, may be considered an upright rectangular prism mounted upon a rectangular base, B, and surmounted by an urn, C; but, considered more in detail, the body is 20 in two sections—an upper section, a, having the form of a rectangular prism, and a lower section, a', whose faces are bowed outward, substantially as shown, and being about equal in height to that of the upper section, but 25 larger in horizontal cross-sectional area. The base B is supported upon the legs b, upon which appears a thistle ornamentation, b'. At its upper edges, b², the base has a smooth finish, and beneath this smooth portion, and 30 between the legs b, vertically-arranged flutings b³ appear. Each side of the base is similarly finished.

The thistle ornamentation is a prominent feature of the entire design. It appears at a² 35 upon the body-section a', at a³ upon the body-section a, at a⁴ at the ends of the body A, and at a⁵ upon the top a⁶ of the stove.

Minor features of the ornamentation are the vertical flutings D at the junction of the sections a a', the alternately-arranged rough and

plain square flutings E just beneath the stove-top, and the horizontally ribbed and leaved member F, forming the cornice of the top.

We claim—

1. The design for a heating stove herein shown and described, the same consisting of the upright prismatic body mounted upon a rectangular base and surmounted by an urn, said body being in sections, the upper one having the form of a rectangular prism and the lower one having its face bowed outward and having the superimposed ornamentation representing thistles arranged as described.

2. In a design for a heating stove, the body herein shown and described, the same consisting of the upright prismatic body made in sections, the upper one having the form of a rectangular prism and the lower one having its face bowed outward and having the superimposed ornamentation representing thistle-work.

3. In a design for a heating stove herein shown and described, the leg-base, the same consisting of the rectangular base and legs made smooth at the upper edges, b², and bearing the ornamentation representing the flutings b³ and the thistle-work b'.

4. In a design for a heating-stove herein shown and described, the top, the same consisting of the top a⁶, having the superimposed ornamentation representing the flutings E, the ribbed and leaved member F, and the thistle-work a⁵.

Witness our hands this 22d day of June, 1888.

HOLMES SMITH.
FRANK A. SEIFERT.
